UNITED STATES PATENT OFFICE.

ROBERT C. MANVILLE, OF WATERBURY, CONNECTICUT.

MACHINE FOR BENDING JACQUARD HOOKS.

SPECIFICATION forming part of Letters Patent No. 515,347, dated February 27, 1894.

Application filed May 15, 1893. Serial No. 474,235. (No model.)

To all whom it may concern:

Be it known that I, ROBERT C. MANVILLE, a citizen of the United States, residing at Waterbury, in the county of New Haven and State of Connecticut, have invented a new and Improved Machine for Bending Jacquard Hooks, of which the following is a true and exact description, reference being had to the accompanying drawings, which form a part thereof.

My invention relates to a machine for bending Jacquard hooks, and has for its object to provide a machine for bending these or similar articles from wire quickly and in such a manner that the resulting bent articles can be relied on always to be uniform; and to this end it consists in certain details of construction and combinations of parts which will be more specifically pointed out in the claims appended to this specification and forming a part thereof.

Heretofore it has been customary to bend Jacquard hooks by hand, first bending the hook (marked w^2 in Figure 10 of the accompanying drawings) which is carried by the lower hook plate, then bending the wire so as to form two arms of suitable length (this bend is marked w^4 in Fig. 10); and finally bending the hook w^3 and trimming it by a cutter or other tool so as to form a suitable hook for the upper hook plate. My hook bending machine, first bending the wire into two arms of suitable length; then, preferably when the wire is held fast by the mechanism which forms the two arms, turns one end of the wire over so as to form a smooth round hook (as w^2) on the end of one arm, and bends the wire sharply so as to turn the end of the other arm into a hook (as w^3) suitable for the upper griff hook; and then when the griff hook has been properly turned, cuts or trims the end thereof so as to give it a proper inclination.

My invention is best understood as described in connection with the drawings in which is illustrated a machine constructed according to my invention and in which—

Fig. 1 is a front elevation of my machine. Fig. 2 is a plan view showing the various cams and operative parts in position. Fig. 3 is a side elevation looking from the left of Fig. 1. Fig. 4 is a detail of a feeding bar taken on the line $x-x$ of Fig. 1. Fig. 5 is a detail of the

feeding device. Fig. 6 is a detail view of the tucker. Fig. 7 is an enlarged detailed view of the mechanism used to turn one of the 55 bends on the Jacquard hook. Fig. 8 is an enlarged detailed view of the mechanism used to bend the other or griff hook on a Jacquard hook. Figs. 9 and 10 are detail views. Fig. 11 is a plan view of the apparatus for bending the hook w^3 shown in operation, and Fig. 12 is a view of the cam which operates the clamping mechanism.

In bending wires to form Jacquard hooks a straight wire as w Fig. 1 is bent to the form 65 shown at w' Fig. 8, the hooks w^3 and w^3 are respectively turned and bent, and the end of hook w^3 is then trimmed so as to form a suitable griff hook.

In my machine for forming Jacquard hooks, 70 T is a table supported on suitable standards T^10 , and having journaled to it in supporting standards as T^5 shafts C C^{10} and a driving shaft R. The shafts C C^{10} are driven by means of gears D^{20} C^{20} on the shafts R and C 75 respectively and bevel gears as cc connecting the shafts C C^{10} . On the shafts C C^{10} are certain cams as $C' C^2$, &c., which serve to actuate a series of bending and other mechanisms which form a finished Jacquard hook from a 80 straight piece of wire. Supported on the table T by means of standards a^5 is a support or feeding board t on which straight pieces of wire are placed of a suitable length; guides t' serve to conduct the wires into a 85 vertical slot or groove t^2 formed in the upright standards a^5 , which are preferably made laterally adjustable to serve for different lengths of wires. In the sides of the standards a^5 are arranged feeding mechanisms, 90 which, as shown, consist of two beveled plates D fitted in and guided in corresponding recesses in the standards a^5 . These plates are provided with flanges d^3 which project across the slots t^2 , and these flanges d^3 have each an 95 oblique slot d with an upper cam face d' which serves to separate single wires and feed them to the bending mechanisms. This bending mechanism consists first, of a tucker A for bending a wire at w^4 , as shown in Fig. 10 so 100 as to form two arms w^7 w^8 ; and the relative length of these arms will be determined by the position of the tucker A relatively to the wire; and as the position of the wire can be

adjusted by shifting the standards a^5 any desired length or size of hook can be made.

The construction of the tucker A and its coacting mechanism is best shown in Fig. 6, 5 where the tucker A is shown in perspective. On a frame P secured to the table T is fastened a plate A', behind this is the tucker A which has a recess or slot a of sufficient width to embrace and fit over the plate A', grooves 10 as a' a^2 are arranged as shown in which the wire fits which is to be bent. The tucker is properly guided by guides as a^6 and is reciprocated by a link c^{11} which is operated by a roller working in a pull and push cam C¹¹, 15 which is preferably so arranged as to give a slow forward movement and a quick return so as to move the tucker A slowly when it is bending a wire and withdraw it quickly when the hook is completed.

20 The bending mechanism consists of several devices which will be described in detail. On a standard n^4 secured to the table T, (as best shown in Fig. 7,) is pivoted a plate N which has a vertical hole n^5 formed in its front end; 25 in said hole is secured a hollow sleeve N' so that it will turn in the hole in the plate N. On the lower end of the sleeve is formed a small gear n , and below the gear n is conveniently arranged a guide wheel n' in which 30 is secured a pin n^2 . Within the sleeve N' is a spindle O which is secured to a pivoted lever c^6 , which lever is operated by a cam C⁶ to raise and lower the spindle O at proper times. The lever c^6 has a head o' with a slot o^2 therein and 35 is secured on the upper end of the spindle by a bolt as o . Pivoted at m' is a segmental rack M which is arranged to engage with the gear wheel n ; the teeth m^3 of this rack are eccentric to the pivotal point m' , that is, the 40 teeth at m^4 are farther from the pivot m' than are those at m^5 , but by adjusting the pivot m' in the slot m^2 of the rack this eccentricity can be changed as desired. The rack M is also preferably provided with a guide at m^7 45 which fits around the guide wheel n' , and is operated by a link m pivoted to the rack and to an arm c^5 which is actuated by a suitable cam C⁵. A frame G is arranged on the table T in front of rack M just described and carries and guides other devices which are best 50 shown in Figs. 8 and 11. To a rod H secured to the frame G is fastened a light spring h which tends to hold the lever c^4 which is pivoted at h' in a raised position. To this lever c^4 at one end is secured a flap as h^2 and at the 55 other end a roller which engages a cam C⁴ which operates on occasions to depress that end of the lever which carries the flap h^2 for a reason to be hereinafter explained. Sliding 60 in a bevel groove g^4 in the frame G is a rack G' which is provided with teeth at g' and is pivoted at G^2 to the arm c^3 which is operated by a suitable cam C³ to reciprocate the rack G'. Secured between two journals G⁵ G⁶ on the face 65 of the frame G is a gear wheel G³ whose teeth g^3 mesh with the teeth of the rack. Arranged to revolve with said gear wheel G³ but free to

move vertically through the gear wheel G³ is a spindle G⁴; this spindle has a pin g^4 secured therein which fits in a helical groove g^5 formed in the lower journal G⁶ and the result of this construction is to rotate and reciprocate the spindle G⁴ when the gear wheel is rotated by the reciprocation of the rack G'. To the lower end of the spindle G⁴ as best seen in Fig. 10 70 is adjustably secured by means of a screw as g^{10} the chuck G¹⁰ carrying a suitable cutter g^{11} . To the front of the frame G and partly covered as shown by an extension G¹² thereof is another frame B⁵; in a slot b^5 in this frame 80 is arranged a block c' which is reciprocated by a cam C'; to this block is pivoted at b^6 a block b which has secured to it a head b' which is normally held in the position shown in Fig. 8 by a spring as b^8 . In the path of 85 the head b' as it is reciprocated by the cam C' is placed a bevel cam B which is adjustably secured to the frame B⁵ by a screw as B'. At one side of the head b' as more clearly shown in plan in Fig. 11 is a former B² which 90 has a specially formed end b^{10} shaped on it corresponding to an end b^{11} on the head b' and behind the end b^{10} is a recess b^4 and an incline b^3 is formed on the outside of the former as shown. 95

Directly within and in line with the former B² I arrange a clamping block F; this block which slides in a suitable groove in the frame B⁵ is operated by an arm c^2 which receives motion from a cam C² whose contour is shown 100 in Fig. 12, and which operates to push forward the clamping block a short distance so as to form a stop for one end of the wire when it is bent (in a manner to be explained) then it pushes the clamping block so as to hold 105 the end of the wire, which fits in a groove as f in the face of the clamping block F, tightly between itself and the end of former B² and finally completely withdraws the clamping block. At the side of the clamping block F 110 as shown in Fig. 11 is secured a bracket f² which extends a short distance in front of the block but which does not come up to the top of the block but only so high that the wire can rest on the bracket in line with the groove 115 f in the block before it is securely held between the clamping plate and the former. When the wire is completely bent as desired and the clamping plate is withdrawn so far that the bracket f² no longer supports the 120 wire then the mechanism best shown in Fig. 6, comes into play to push the wire down through the slot S in the table T where it is guided by an incline S' into a suitable receptacle S²; this mechanism consists of a spindle p which is moved up and down at proper times by a lever c⁷ operated by a cam C⁷ and which carries a foot p² which has two forks 125 p³ which fit over the plate A'. 130

The manner of operation is as follows: A 130 number of wires of approximately suitable length are placed on the feed board t and being rolled to the front of it fall down in the slot t² and pile up in the manner shown in

Figs. 1 and 5. On setting the machine in motion the feeders D move forward and separate one wire at a time and feed it down in front of the tucker A, the ends of the wire resting in the bottom of the groove t^2 , an aperture t^3 being provided as shown in Fig. 5 so that the ends of the wires can be readily pushed out of their position in the groove t^2 when the wire is bent by the tucker. The tucker A then advances and bends the wire at w^4 into two arms of a length governed by the position of the tucker A and plate A'. The ends of the wire as they sweep around are supported on the segmental guides e e', the shorter end of the wire coming against the pin n^2 in the hollow sleeve N thereupon the lever c^6 is depressed and the pin O' comes down on the other side of the wire, which is now held between the two pins in a manner shown in Fig. 9. The rack M is now moved by its actuating cam C⁵ in the direction of the arrow and rotates the sleeve N' and the pin n^2 around the pin O' and at the same time moves the plate N slightly on its axis so that the end of the wire is turned into a neat hook as w^2 . The pin O' is then raised by the cam C⁶ operating through the arm c^6 and this part of the operation is completed. In the meantime the other end of the wire has been carried around in like manner and riding up the incline b^2 of the former B² it rests somewhere on the top of the former block, the flap h² is now depressed and the end h³ of the flap pushes the end of the wire between the former B² and the clamping block F, this clamping block has been removed so far forward that the bracket f² has been put in a position as shown in Fig. 11 so that the end of the wire will not be pushed down too far and when the wire is pushed into proper position the clamping block is so moved by the cam C² as to securely hold the wire. When the wire is thus securely held the head b' is moved forward first bending the wire at right angles over the end b¹⁰ of the former and then, when the rounded face b³ of the head b' strikes the cam B it operates to make a sharp hook in a manner shown in Fig. 11. The hook being formed, the head b' is withdrawn and the cutter g¹¹ on the block G¹⁰ comes down and trims off the end of the hook the cuttings conveniently falling down in the recess b⁴. The cutter is moved up and away, the clamping block fully drawn back, the lever c⁴ is raised, the tucker A pulled back and the now finished hook being free the foot p² is depressed and the hook is pushed through the slot S to the receptacle for finished hooks, the foot p² is raised by the action of its actuating cam C⁷ and the machine is ready for another operation.

It will of course be obvious that various devices can be substituted for many of those shown, and while I have described the parts and arrangement which I deem most useful and convenient I do not wish to be considered as binding myself to the exact construc-

tion shown, and also it is obvious that many of my present devices can be used in other connections than in a machine for bending 70 Jacquard hooks. The bending devices are all adjustably secured to the table T and can be arranged to form any desired size of hook.

Having now described my invention, what I claim as new, and desire to secure by Letters 75 Patent, is—

1. In a machine for bending wire the combination with mechanism for bending lengths of wire, of a guide for the wire and feeders D having inclined slots d adapted to separate 80 and feed a single length of wire from the guide to the wire bending mechanism.

2. In a machine for bending wire, the combination with a plate A' and a tucker for bending the wire over the plate A', of a support for a number of separate lengths of wire, 85 a guide adapted to conduct the wires from the support to feeding mechanism, feeders D for delivering the wire, length by length, between the tucker and plate, and means for 90 operating the feeders and bending mechanism.

3. In a machine for bending wires, the combination with a plate A' and a tucker A for doubling the wire so as to form two arms, of 95 feeders D having inclined slots d for delivering the wires singly between the tucker and plate, and means for operating the feeders and bending mechanism.

4. In a machine for bending wire, the combination with a feeding device for delivering single wires, of a tucker A having a recess a, and grooves a' a², and a plate A' adapted to fit in the recess a substantially as and for the purpose specified. 100 105

5. In a machine for bending wire, the combination with means for bending a piece of wire so as to form two substantially parallel arms, of means for turning over the ends of one of the arms so as to form a rounded hook, 110 and a cam b' and a former B for bending a sharp hook w³ on the other end of the wire substantially as and for the purpose specified.

6. In a wire bending machine the combination with a tucker for bending the wire into 115 two substantially parallel arms, of pins n² O' operating to hold the wire between them, and means to give said pins a simultaneous rotary and longitudinal movement whereby a hook is turned on one end of the wire without pulling it longitudinally.

7. In a wire bending machine, the combination with a tucker for bending the wire into two substantially parallel arms, of pins n² O' operating as described to turn a hook in one 125 arm of the wire, and means for bending the other arm of the wire to form a sharp hook w³, substantially as and for the purpose specified.

8. In a wire bending machine, the combination with a bevel cam B, of a head b' pivoted at b⁶, means to reciprocate said head b' so as to cause it to strike the cam B, and a former B² over which the head b' is adapted to be 130

pushed by the reciprocating mechanism and the cam B.

9. In a wire bending machine the combination with a stationary former, of a beveled cam B, a pivoted head b', means to reciprocate said head so that it will strike and be turned by the cam B, all operating to bend a hook w^3 and cutting mechanism for trimming the end of the hook.

10. In a wire bending machine, the combination with a former B², of a head b' adapted to be moved over said former by means of cams B and C' so as to bend a hook on the end of a wire, a cutter having a combined vertical and rotary motion adapted to trim the hook after it is bent by the head b', substantially as specified.

11. In a wire bending machine, the combination with the tucker A and plate A' for bending the wire so as to form two substantially parallel arms, of a pin n² and clamp F for limiting the movement of the arms as they are bent, an eccentric rack M to rotate and reciprocate the pin n² to turn a hook w^3 in one arm of the wire, and a head b', and former B² for bending a sharp hook w^3 on the other arm of the wire.

12. In a wire bending machine, the combination with the tucker A and plate A' for bending the wire so as to form two substantially parallel arms, of a pin n² and clamp F for limiting the movement of the arms as they are bent, an eccentric rack M to rotate and reciprocate the pin n² to turn a hook w^3 on one arm of the wire, a head b', and former B² for bending a sharp hook w^3 on the other arm of the wire, and a cutter for trimming the hook w^3 .

13. In a wire bending machine, the combination with the tucker A and plate A' for bending the wire so as to form two substantially parallel arms, of a pin n² and clamp F for limiting the movement of the arms as they are bent, an eccentric rack M to rotate and reciprocate the pin n² to turn a hook w^3 on one arm of the wire, a head b' and former B² for bending a sharp hook w^3 on the other arm of the wire, a cutter for trimming the hook w^3 , and a pivoted lever c⁷ for pushing the wire downward through a slot in the supporting table when bent as desired.

14. In a wire bending machine the combination with a plate A' and tucker A, of the

sleeve N' having a gear n secured thereto, an eccentric rack M for rotating and reciprocating said sleeve, a pin O' and a pivoted lever c⁶ for moving said pin vertically, as and for the purpose specified.

15. In a wire bending machine the combination with means for bending the wire so as to form two arms, of a pivoted frame N having a hole n⁵ inclosing a hollow sleeve N', and a reciprocating spindle O arranged within the sleeve N', a pivoted lever c⁶ to reciprocate the spindle O, an eccentric rack M to rotate and reciprocate the sleeve N', and pins n² and O' arranged on the sleeve and spindle respectively, as and for the purpose specified.

16. In a machine for bending wires for Jacquard hooks, the combination with feeders D for feeding wires singly, a tucker and plate for bending the wires fed to it by the feeders into two substantially parallel arms, a rotating and reciprocating pin for turning a hook w^3 on one arm, a head b' operating as described for bending a sharp hook w^3 on the other arm, and a cutter for trimming the last named hook, substantially as specified.

17. In a machine for bending wires for Jacquard hooks, the combination with feeders D for feeding wires singly, a tucker and plate for bending the wires fed to it by the feeders into two substantially parallel arms, a rotating and reciprocating pin for turning a hook w^3 on one arm, a head b' operating as described for bending a sharp hook w^3 on the other arm, a cutter for trimming the last named hook, a fork shaped foot p fitting over the plate A', and means to reciprocate it to push a finished hook off from the machine.

18. In a wire bending machine the combination with means for holding the wire in a fixed position, of bending mechanism adapted to operate on the wire at a point unequally distant from its ends whereby a U shaped piece is formed having arms of different lengths, a bending device adapted to operate on the shorter arm near its end to form a rounded hook, means for bending a sharp hook on the long arm and a cutter for trimming the hook thus formed.
